(74) Attorney, Agent, or Firm—Caesar, Rivise, Bernstein, Chen & Pokotilow, Ltd.

(57) **CLAIM**

The ornamental design for a switchplate, as shown and described.

DESCRIPTION

FIG. 1 is a front view of a switchplate showing my new design.

FIG. 2 is an end view thereof;

FIG. 3 is a side view thereof;

FIG. 4 is a front view of a second embodiment of a switchplate showing my new design.

FIG. 5 is an end view thereof;

FIG. 6 is a side view thereof;

FIG. 7 is a front view of a third embodiment of a switchplate showing my new design.

FIG. 8 is an end view thereof; and,

FIG. 9 is a side view thereof.

The broken lines shown in FIGS. 1-9 are for illustrative purposes only and form no part of the claimed design.
